SHOCK AND VIBRATION PROOF RECEP-
TACLE FOR ELECTRIC LAMPS

James N. McTwiggan, United States Navy

Application March 4, 1932, Serial No. 596,829

4 Claims. (Cl. 173—342)

(Granted under the act of March 3, 1883, as
amended April 30, 1928; 370 O. G. 757)

This invention relates to a receptacle for electric lamps designed to prevent injury to the lamps by jarring or vibration of the wall or other body to which the receptacle is affixed.

It is the object of my invention to provide a receptacle that will absorb vibration and shocks and not transmit them to a lamp mounted therein.

With the above and other objects in view, the invention consists in the construction, combination and arrangement of parts as will be described more fully hereinafter.

Reference is to be had to the accompanying drawing forming a part of this specification, in which like reference characters indicate corresponding parts throughout the several views, and in which:

Figure 1 is a side elevational view of my invention;

Figure 2 is a longitudinal section thereof on the line 2—2, Figure 1;

Figure 3 is a plan view, looking into the socket of the receptacle.

Electric lamps are used in many places, such as on ships, railroad cars, bridges, etc., where the lamps are subjected to heavy shocks and more or less constant vibration that have a destructive effect on the filaments unless some type of shock-absorbing mounting is employed. Tests have shown the life of a lamp to be several times longer when mounted in receptacles embodying my invention than in receptacles previously used.

The base 4 is preferably of some insulating material having the necessary mechanical strength, with a flange 5 in which are suitable threaded apertures to receive the screws 7 to bind to the base the wires 8 and 9 that supply the current to the lamp and the wires that connect to the feed lines.

Socket 10 is likewise of insulating material and has a bulbous anchoring portion 11. Screw threaded bushing 12 in the socket is of conducting material, such as copper, and forms one of the connections between the receptacle and the filament, as is common practice. Anchoring portion 11 is embedded in sponge rubber 13 or equivalent material, preferably in the form of rings, as shown, disposed in base 4 where it is retained by flange 14 on the interior of the base and cap 15 screwed therein. The rings of material 13 around anchoring portion 11 are stretched in placing them on that portion so they are under tension and have a substantial frictional contact therewith. The base 4 holds the sponge rubber under constraint and prevents excessive yielding and deformation thereof and thus makes it im-

possible for the anchoring portion to pull out of the rubber. Wire 9 is connected to resilient metal tongue 16 that bears against the filament terminal in the end of the neck of the lamp. Wire 8 is connected to bushing 12. Tongues 17 on base 4 project into slots 18 in socket 10 to prevent rotation of the socket when a lamp is being screwed into or out of the socket. Wires 8 and 9 are made slack so that no vibration will be imparted to socket 10 through them.

It is apparent that a lamp hung in one of these receptacles will be thoroughly insulated against mechanical disturbances to which the base is subjected, owing to the very small elasticity (in the scientific sense) of the sponge rubber by which the socket 10 is supported from base 4.

It will be understood that the above description and accompanying drawing comprehend only the general and preferred embodiment of my invention, and that various changes in construction, proportion and arrangement of parts may be made within the scope of the appended claims, without sacrificing any of the advantages of my invention.

The herein described invention may be manufactured and used by or for the Government of the United States for governmental purposes without the payment of any royalty thereon.

I claim:

1. A lamp receptacle, comprising a hollow base, an inwardly extending flange in said base, a plurality of rings of sponge rubber in said base, a socket having a bulbous anchoring portion seated inside said rings, a threaded electrically conducting bushing in said socket, slack conducting means connected to said bushing, a resilient metal tongue in said socket, slack conducting means connected to said tongue, a closure secured to said base to retain said rings therein, and interengaging parts on said base and said socket to prevent relative rotation of the base and the socket.

2. A lamp receptacle, comprising a hollow base, a plurality of rings of sponge rubber in said base, a socket having a bulbous anchoring portion of substantially greater diameter than the holes in said rings within which said portion is disposed, means to retain said rings in said base, a conducting bushing and a resilient metal tongue in said socket, conducting means connected to said bushing, other conducting means connected to said tongue, and means to prevent relative rotation of said socket and said base.

3. A lamp receptacle, comprising a hollow base, a plurality of rings of sponge rubber in said base,

a socket having a bulbous anchoring portion, the said portion being disposed inside said rings and placing said rings under radial stress whereby said rings have an effective frictional grip upon said portion, means to retain said rings in said base, and means in said socket to conduct current to a lamp operatively mounted therein.

4. A lamp receptacle, comprising a hollow base, a plurality of rings of sponge rubber in said base,

a socket having a bulbous anchoring portion, the said portion being disposed inside said rings and the said rings having sufficient frictional engagement with said portion to prevent relative sliding movement of said portion with respect to said rings, means to retain said rings in said base, and means in said socket to conduct current to a lamp operatively mounted therein.

JAMES N. McTWIGGAN.
